UNITED STATES PATENT OFFICE.

OLE O. KOLSTAD, OF DULUTH, MINNESOTA.

MAIL BOX.

Application filed January 26, 1925. Serial No. 4,645.

This invention relates to mail boxes, and particularly to a receptacle for containing a plurality of individual boxes.

The principal object is to provide a neat, attractive and practical nest of mail boxes applicable to apartment houses, tenement hotels, flats, or for roadside mail service.

Other objects and advantages of the specific construction will appear in the further description thereof.

Referring now to the accompanying drawing, forming part of this application and in which like reference characters indicate like parts:

15 Figure 1 is an elevation of one of the improved mail box receptacles;

Figure 2 is a central vertical section of Fig. 1;

20 Figure 3 is a plan view of a modified arrangement of a nest of boxes; and

Figure 4 is a still further modified cluster, shown in cross section for a clearer comprehension of the receptacle construction.

In the preferred form of cylindrical nest 25 of boxes a base is illustrated at 1, supporting a tubular stem 2 which carries upon a suitable ball or other frictionless bearing 3 the cylindrical skeleton-like receptacle comprising the tubular central support 4, mounted upon the 30 circular block 5 at the base and carrying the circular block 6 at the upper end thereof, said tube being spaced some considerable distance from the stem 2, that is being considerably larger in diameter, and carrying 35 radially thereupon any desired number of partitions or division walls 7. In the embodiment here shown I have illustrated twelve such division walls so that twelve boxes may be installed therebetween in one tier of the complete circular receptacle. As 40 a particularly practical arrangement I have shown the receptacle as comprising three such tiers, or in all thirty-six boxes.

In this arrangement there would be three 45 circular floors indicated at 8, each floor being surrounded circumferentially by a flat, upstanding flange indicated at 9 to prevent the boxes from falling out and each box being substantially segmental in shape rests upon 50 its respective floor 8 in behind the flange 9. The boxes are illustrated at 10 and have no direct connection to the receptacle whatever, and terminate somewhat short of the full depth of each segmentally shaped compartment. For convenience in the mounting and 55 manipulation of the operating levers 11, one

end of the lever is pivotally mounted as at 12 at practically a central point in the back of each box and the opposite end of each lever 12 is pivotally attached as at 13 to the outer wall of the operating tube 14 which loosely surrounds the spindle 2 and is vertically reciprocably mounted thereupon.

At one side of the upper end of the operating tube 14 is pivotally attached as at 15 60 the operating lever 16 which extends through the suitable opening in the block 6, and is attached as at 17 to the manually engageable lever 18. This lever 18 is pivotally attached as at 19 about the upper head ring 20 65 of the receptacle and lies normally upon the upper surface of the conically shaped top 21 of the receptacle. The lever 18 is shown as of double construction and provided with the upright handle portion 22 and may be provided with any desired form of regulation 70 mail box lock at the point indicated at 23, so that the entire nest of boxes may not only be operated simultaneously by the operation of the lever, but are secured against tampering 75 by the locking of said lever, the lock being controlled by the mail carrier only.

By this attachment it is apparent that when the free end of the lever 18 is raised the tube 14 will also be raised and carry 80 with it the levers 11, which, being pivotally attached to the various boxes will tip them forwardly as indicated in dotted lines Figure 2, their upper side edges being arcuate 85 in shape permitting of such forward tipping. When the boxes are thus tipped forward, it is apparent that their upper ends become available for the deposit of mail and when the lever 18 is depressed as illustrated 90 in the drawing all the boxes will be simultaneously closed. For access to the boxes individually, I prefer to have the whole front of each box hinged in any desired manner upon one side, and provided with a suitable lock upon the opposite side as indicated at 95 100 24, whereby each owner may have access to his individual box; and these fronts are each provided adjacent the upper end with the usual name plate indicated at 25, with a very narrow elongated slot 26 just below same 105 for the reception of calling cards or the like. Spaced upwardly from the lower edge of the door are two sight holes 27 through which anything deposited in the box becomes 110 visible.

In Figure 1 I have illustrated a laterally extending arm or bracket 28 upon which a

telephone arm 29 may be pivoted as at 30 if so desired, and in the event of such a nest of boxes being used out of doors, for example in the rural delivery of mail, the spindle 2 could be extended somewhat and an umbrella-like roof arranged over same to afford protection from the elements.

I have shown in Figure 3 an installation embodying the application of the invention to the corner of a room, wherein but a quarter of the circular arrangement of boxes such as shown might be employed, and in Figure 4 is a group comprising a semi-circular arrangement of the boxes, and, as is obvious the boxes may be of any desired shape, number or size, and yet fall within the general grouping plan.

The convenience of such a device is readily appreciated from the standpoint of the mail carrier, in that he may step up to such a receptacle, unlock and raise the operating lever, when all of the boxes simultaneously open by being tipped outwardly radially, and he can fill the nearest boxes and rotate the receptacle until all boxes are served.

Having thus described my invention, what

I claim and desire to secure by Letters Patent, is:

1. A device of the character described comprising in combination a rotatable rack, 30 an axial support for said rack, a plurality of radially disposed boxes in said rack, reciprocal means about the axis of the rack for simultaneously tipping all of the boxes in the rack, said means being controllable 35 from the top of the rack.

2. A group of mail boxes assembled radially about a single support, reciprocal means to which each box is attached, and means attached to said reciprocal means 40 for causing the same to simultaneously open each box.

3. A group of radially operable mail boxes assembled about a single support, reciprocal means about said support, connecting 45 means pivotally uniting each box with said reciprocal means, and means for causing the reciprocal means to simultaneously open each box.

In testimony whereof I hereunto affix my 50 signature.

OLE O. KOLSTAD.
